ART OF MOUNTING TELEVISION RECEIVING ANTENNAS

Ernest O. Johnson, Haddonfield, N. J., assignor
to Radio Corporation of America, a corporation
of Delaware

Application July 31, 1946, Serial No. 687,477

1 Claim. (Cl. 250—33.51)

1

This invention relates to the art of mounting masts, and will be described as applied to the mounting of an antenna mast for a home television receiver upon the exterior wall of a house having an overhanging roof.

The usual television receiving antenna comprises a dipole which, for optimum performance, should be oriented in a horizontal plane. When the vertical mast upon which the dipole is mounted is to be supported upon the outer wall or upon a window frame of a house having an overhanging roof considerable difficulties may be encountered in the vertical alignment of the mast. As a result, television-set manufacturers have heretofore left antenna installation problems to the ingenuity of the purchaser and this has led, in some cases, not only to faulty reception but to fire hazards as well.

Accordingly, the principal object of the present invention is to obviate the foregoing and other less apparent objections to present day receiving-antenna installations and to provide an improved installation which though made of parts of standard dimensions shall be capable of being applied to buildings having various roof and window sill dimensions.

The invention will be described in connection with the accompanying drawing, wherein:

Figure 1 is a view in perspective of a television receiving antenna mounted in accordance with the principle of the invention upon the exterior wall of a house, and

Figure 2 is an enlarged view in perspective of one of the mounting brackets for the antenna mast shown in Figure 1.

In the drawing, 1 designates, generally, a house having an exterior side wall 2, an overhanging roof 3, and a window frame 4 which includes an upright frame portion 5 and a sill portion 6 which project different distances from the plane of the exterior wall 2 beneath the overhanging portion 3a of the roof. Two mounting brackets 7 and 8, later described, are mounted one above the other upon the upright portion 5 and the sill portion 6 of the window frame and are long enough to extend well beyond the overhanging portion 3a of the roof. The distance between upper and lower brackets 7 and 8 should not be less than one-quarter the length of the antenna mast 9 above the upper bracket 7 and the height of the antenna 10 on the upper end of the mast should not be greater than ten feet above the upper bracket 7.

In the instant case, since the lower bracket 8 is mounted on the sill portion 6 of the window frame, it projects farther from the plane of the

wall 2 than the upper bracket 7 which is mounted on the upright portion 5 of the said frame. This virtual inequality in the length of the brackets 7 and 8 would ordinarily dictate the use of shims 5 or the use of brackets of various lengths, but is compensated for, in accordance with the present invention, by the use of duplicate brackets of the special construction shown in Fig. 2.

The brackets 7 and 8 each comprise a triangular metal frame and an auxiliary brace in the form of a rod or bar 11. As shown in Fig. 2 the frame comprises a right angled triangle formed of a unitary right angled piece 12 and inclined piece 13 which is secured to the opposite ends of the first piece as by welds (not shown). The short arm or base 12a of the triangle is provided with mounting holes *h* and *h*₁ adjacent to its ends and the arm 12b which extends normal to the base 12a is provided with a number (in this case, eight) of longitudinal slots *s*—*s*₈ for the reception, at a selected distance from the base 12a of a U-bolt 14 within which the mast 9 is held by means of a suitably shaped clamping plate 15 and by nuts 16 and washers 17 on the threaded arms of the U. The brace 11 for the bracket is provided at its inner end with an apertured tab 11a for attachment to the window frame 4 (Fig. 1) and at its outer end with a number of spaced holes *m*—*m*₅ so that it may be affixed to the projecting arm 12b as by means of a bolt 18 at a selected point determined by the relative projection of the part of the window frame to which the base 12a of the bracket is affixed.

In mounting the duplicate brackets 7 and 8 upon the window frame 4 the preferred practice is to hold each bracket and its brace 11 in place, mark the mounting holes *h* and *h*₁ on the frame and drill (say) $\frac{1}{8}$ " holes for one inch lag screws (not shown). Since the brace 11 for each bracket can be pivoted on its bolt 18 at the outer end of the bracket it may be shifted either down (as on the upper bracket 7) or up (as on the lower bracket 8) in attaching it to the frame 4. When the brackets 7 and 8 are in place and their U-bolts aligned by mounting them in selected ones of the slots *s*—*s*₈ the nuts 16 are tightened to hold the mast 9 in place.

The mast 9 may comprise simply a one inch galvanized water pipe through which the transmission line 19 extends downwardly from the antenna 10 to a point preferably below the window sill 6. The mast must be grounded, as by means of a wire 20 which is connected at its lower end to a metal ground rod 21 driven into moist earth. Screw eye insulators 22 suitably spaced

on the exterior wall 2 of the building serve as supports for the exposed length of the transmission line 19, which in the instant case enters the house through a hole drilled preferably on an upward slant in the frame of a cellar window 23. A "rain drip loop" 19a in the lower end of the transmission line prevents water from running along the line toward the window 23.

It will now be apparent that the present invention provides a simple, inexpensive and trouble-free means for mounting a television or similar mast upon the exterior of a building having various roof and window sill dimensions.

What is claimed is:

Television receiving-antenna apparatus comprising means for mounting a mast upon the exterior of a building having an overhanging roof and a window frame including upright and sill portions which project different distances from said building-exterior beneath the overhanging portion of said roof, said apparatus comprising a pair of triangular brackets provided with mounting means on corresponding base-sides of said triangles whereby said brackets may be mounted one above the other on said differently projecting portions of said window-frame, said brackets being in the form of right triangles of duplicate construction and dimensions, a dipole adjacent the upper end of said mast, notched

U-shaped clamping plates, one for each bracket, for securing said mast in a vertical position to a projecting arm of each bracket at a selected distance from its base-side sufficient to clear the overhang of said roof, a brace for each bracket adapted to be attached at one end to said window frame and at the other end to a selected point on said projecting arm determined by the relative projection of the part of said window frame to which said base of said bracket is affixed, and means whereby said mast carries a leadin.
